UNITED STATES PATENT OFFICE.

RUDOLPH MAGOSY, OF NEW YORK, N. Y.

DESIGN FOR A MUTE.

Application filed October 15, 1925. Serial No. 15,141. Term of patent 14 years.

To all whom it may concern:

Be it known that I, RUDOLPH MAGOSY, a citizen of the United States of America, and resident of New York, county and State of New York, have invented a certain new, original, and ornamental Design for Mute, of which the following is a specification, reference being had to the accompanying drawing, forming part thereof.

In the drawing:—

Fig. 1 is an elevation of a mute showing my new design.

Fig. 2 is a bottom plan view of the same; and

Fig. 3 is a top plan view thereof.

I claim:

The ornamental design for a mute, as shown.

RUDOLPH MAGOSY.
